Primary Examiner — Cynthia M. Chin*(74) Attorney, Agent, or Firm* — Knobbe Martens Olson & Bear, LLP(57) **CLAIM**

The ornamental design for a scooter, as shown and described.

DESCRIPTION

FIG. 1 is a perspective view showing a front, side and top surface of a scooter.

FIG. 2 is a front view of the scooter of FIG. 1.

FIG. 3 is a rear view of the scooter of FIG. 1.

FIG. 4 is a right side view of the scooter of FIG. 1.

FIG. 5 is a left side view of the scooter of FIG. 1.

FIG. 6 is a top view of the scooter of FIG. 1; and,

FIG. 7 is a bottom view of the scooter of FIG. 1.

Where utilized, the broken lines show portions of the scooter that form no part of the claimed design.

1 Claim, 7 Drawing Sheets
